Patented April 12, 1904.

UNITED STATES PATENT OFFICE.

LOUIS V. ARONSON, OF NEWARK, NEW JERSEY.

DESIGN FOR A PAPER-WEIGHT.

SPECIFICATION forming part of Design No. 36,872, dated April 12, 1904.

Application filed February 23, 1904. Serial No. 194,957. Term of patent 3½ years.

To all whom it may concern:

Be it known that I, LOUIS V. ARONSON, a citizen of the United States, residing at Newark, in the county of Essex and State of New Jersey, have invented a new, original, and ornamental Design for a Paper-Weight, of which the following is a specification, reference being had to the accompanying drawings, forming a part thereof.

10 Figure 1 is a front elevation of a paper-

weight embodying my new design. Fig 2 is an end elevation of the same, and Fig. 3 is a plan view of the paper-weight.

What I claim is—

The ornamental design for a paper-weight 15 as shown.

LOUIS V. ARONSON.
